Primary Examiner — Vy N Koenig*Assistant Examiner* — Omeed Agilee(74) *Attorney, Agent, or Firm* — Panasonic IP Management; Kerry S. Culpepper**CLAIM**

I claim the ornamental design for a package, as shown and described.

DESCRIPTION

FIG. 1 is a front, top and left perspective view of a package, showing my new design;

FIG. 2 is a front view;

FIG. 3 is a rear view;

FIG. 4 is a left side view thereof;

FIG. 5 is a right side view thereof;

FIG. 6 is a top view thereof;

FIG. 7 is a bottom view thereof;

FIG. 8 is a sliced section view of the package, taken between broken line arrows 8-8 in FIG. 2; and,

FIG. 9 is a top plan view of a package in an unassembled blank configuration.

The broken lines in the drawings represent fold lines that form no part of the claimed design.
